(57) **CLAIM**

I claim the ornamental design for a mast base connector, as shown and described.

DESCRIPTION

FIG. 1 is a top front quarter perspective view of a first embodiment of a mast base connector;

FIG. 2 is a top rear quarter perspective view thereof;

FIG. 3 is a bottom rear quarter perspective view thereof;

FIG. 4 is a bottom front quarter perspective thereof;

FIG. 5 is a front view thereof;

FIG. 6 is a rear view thereof;

FIG. 7 is a right view thereof;

FIG. 8 is a left view thereof;

FIG. 9 is a top view thereof;

FIG. 10 is a bottom view thereof;

FIG. 11 is a top front quarter perspective view of a first embodiment of a mast base connector;

FIG. 12 is a top rear quarter perspective thereof;

FIG. 13 is a bottom rear quarter perspective view thereof;

FIG. 14 is a bottom front quarter perspective view thereof;

FIG. 15 is a front view thereof;

FIG. 16 is a rear view thereof;

FIG. 17 is a right view thereof;

FIG. 18 is a left view thereof;

FIG. 19 is a top view thereof; and,

FIG. 20 is a bottom view thereof.

The broken dot-dash lines shown in FIGS. 1-5, 7-9, 11, 13-15, 17 and 18 illustrate the bounds of the claim. The remaining broken lines shown in FIGS. 1-5, 7-16, and 17-20 illustrate portions of the mast base connector and form no part of the claimed design.

1 Claim, 20 Drawing Sheets
